UNITED STATES PATENT OFFICE.

HENRY B. WALKER, OF LANCASTER, OHIO.

PUMP.

1,272,737.

Specification of Letters Patent. Patented July 16, 1918.

Application filed April 14, 1916. Serial No. 91,163.

To all whom it may concern:

Be it known that I, HENRY B. WALKER, a citizen of the United States, and resident of Lancaster, in the county of Fairfield and State of Ohio, have invented a new and useful Improvement in Pumps; and I do hereby declare the following to be a full, clear, and exact description thereof.

My invention relates to pumps more especially adapted for oil and like deep wells.

The object of my invention is to provide a pump of this character of double-acting type so that the fluid is raised by both the downward and upward movements of the piston; thereby greatly increasing the capacity of the pump.

To these ends my invention comprises the novel features hereinafter fully set forth and claimed.

20 In the accompanying drawing, Figure 1 is a vertical section of my improved pump and Figs. 2 and 3 are sections on the lines 2—2 and 3—3, respectively, of Fig. 1.

In the drawing, the numeral 2 designates 25 a stationary barrel or casing at the lower end of the well, said casing having the perforations 3 in its walls and closed at its lower end by the cap 4. The upper end of the casing or barrel 2 is threaded into the connection 5.

30 Suspended within the connection 5 on the inclined shoulder 6 in the interior thereof is the working-barrel 7, said working barrel being screwed into the head 8, said head having the ground-seat 9, which rests upon the inclined shoulder 6, forming a tight joint therewith. The working-barrel 7 may be made up of several sections connected by the threaded sleeves 10^a and 10^b, having the bores 11.

40 Suitable packing material 12 engages the interior shoulder-positions 13 of the working-barrel, and springs 14 are interposed between said packing material and the sleeves 45 10^a and 10^b, said springs acting to hold said packing material 12 securely in place, and with sufficient force to expand said packing material to form a tight joint between said packing material and the eduction-tube 15 for the purpose more fully hereinafter set forth.

45 This eduction-tube 15 passes down through the bore 16 of the head 8, said eduction-tube being formed in sections connected 50 by sleeves 17 and 20. The upper pumping-

piston 18 is of the ordinary type with the cups 19; and said piston surrounds the eduction-pipe, being located between the sleeve 17 and the sleeve 20, said pumping-piston having a certain amount of play between 60 said sleeves, such as the space 21.

Openings 22 are formed in the eduction-pipe at the space 21 between the pumping-piston and the lower sleeve 20 to admit fluid to the eduction-pipe when the upper pumping-piston is lowered, as will more fully 65 hereinafter appear.

Between the pumping-piston and the connecting sleeve 10^a is the space 23 for the accumulation of fluid. In this space 23 is 70 located the valve 24, said valve consisting of a split-ring 25, formed of leather or other suitable material, and secured to the working-barrel by rivets 26. Within the split-ring 25 is the split spring-steel band 27, 75 which is secured to said split-ring 25 by the rivets 26 and the rivets 28. This spring tends normally to force the split-ring 25 out against the inner walls of the working-barrel 7, and acts to close the openings 29 80 formed in said working-barrel.

A valve 24^a of like character is located farther down in the working-barrel below the sleeve 10^b in the space 23^a, and is adapted to control the supply of fluid entering the 85 openings 29^a.

The lower end of the eduction-pipe 15 carries a pumping-piston 30, which carries the valve 31 resting on the seat 32. Said pumping-piston also has the openings 33 for 90 the admission of the fluid contained within the space 23^a.

The lower end of the working-barrel is provided with the perforated plug 34.

The upper end of the eduction-tube has 95 the valve 35, and above said valve, the perforated cap 36.

The tube 37, is threaded into the connection 5.

In the operation of my improved pump, 100 when the eduction-pipe is raised by the wire line or other connection leading to the ordinary walking-beams or other reciprocating device at the top of the well, the pumping-pistons are raised and the fluid contained in the space 23^a is forced through the openings 33 of the pumping piston 30 and passes up into the eduction-pipe 15. At the same time, by the raising of the eduction-pipe, the 105 upper pumping-piston being retarded in its 110

upward movement by the cups, will permit the sleeve 20 to move up and engage the seat 19^a on the lower end of the pumping-piston 18, thereby closing the openings 22. As the 5 pistons ascend, the vacuum created in the space 23, will act on the split-ring 25 so as to open the openings 29, and fluid passes from the outer casing or barrel 2 into said space 23, which increases in capacity as the 10 pumping-piston rises; and said space becomes filled with the fluid, which is held therein due to the closing of the openings 22. In the meantime, the fluid, which has passed from the space 23^a through the openings 33 and valve 31 to the eduction-pipe 15, 15 is being lifted by the upward movement of the eduction-pipe to the top of the well.

On the descent of the pumping-pistons, the sleeve 20 will move away from the seat 20 19^a of the upper pumping-piston 18; and as said pumping-piston descends, the fluid contained within the space 23, will be forced through the openings 22 into the eduction-pipe, the valve 25 having closed the openings 29 so that as the piston descends, the fluid contained within the space 23 is forced 25 through the openings and up through the eduction-pipe to the top of the well. At the same time, the piston 30 at the lower end, 30 in its descent, through the suction causes the valve 24^a to open, admitting fluid by the openings 29^a into the space 23^a, until said space becomes filled with fluid, which, upon the upward movement of the piston, passes 35 as before described through the openings 33 and valve 31 into the eduction-pipe. In this manner, I provide a double-acting pump for oil or like deep wells in which the fluid is raised by both the upward and downward 40 strokes of the pump, and in this way, the capacity of the pump is greatly increased.

What I claim is:

1. In a pump, the combination of a working-barrel, a plurality of pumping pistons 45 therein, an eduction-pipe, fluid chambers in the working-barrel between the pistons communicating with said pipe, and means for alternately forcing fluid from the chambers into the eduction-pipe by reciprocation of the pistons.

2. In a pump, the combination of a working-barrel, a plurality of pumping pistons therein, an eduction-pipe, fluid chambers in the working-barrel between the pistons communicating with said pipe, valve-controlled 55 openings in said chambers adapted to be opened by suction created by the pistons, and means for alternately forcing fluid from the chambers into the eduction-pipe by reciprocation of the pistons.

3. In a pump, the combination of a working-barrel, a plurality of pumping-pistons contained therein, an eduction-pipe, openings forming communication between said 65 eduction-pipe and said working-valve, open-

ings in said working-barrel between the pistons, spring-controlled valves normally closing said openings, means for opening said valves by the suction created by the pumping-pistons whereby fluid enters said working-barrel, means for trapping said fluid in said working-barrel by the movement of said pumping-piston, and means for opening communication between the eduction-pipe and said working barrel, whereby the fluid 75 trapped therein is raised by the downward movement of one pumping piston and the upward movement of the other alternately.

4. In a pump, the combination of a working-barrel, a plurality of pumping pistons 80 contained therein, an eduction pipe within said working-barrel, and forming spaces between the pistons for trapping the fluid between said working-barrel and said eduction-pipe, openings in said eduction-pipe 85 leading into said spaces, valve controlled openings in said working-barrel leading into said trapping spaces, means for opening said openings by the suction created by said pumping-pistons, whereby the fluid is admitted alternately to said trapping spaces and means for closing communication between said eduction-pipe and one of said trapping spaces by the upward movement 90 of said pumping plungers, and opening communication between the other trapping space and said eduction-pipe whereby the fluid is permitted to enter said eduction-pipe and is raised therein by the pumping-plunger.

5. In a pump, the combination of a working-barrel, a plurality of pumping-pistons contained therein, an eduction-pipe on which said pumping-pistons are mounted, one of said pumping-pistons slidable on said eduction-pipe, openings in said eduction-pipe 105 communicating with a trapping space formed between said eduction-pipe and working-barrel, means for closing said openings by said slidable pumping-piston moving over said openings, valve-controlled 110 openings in said working barrel, means for opening said openings by the suction created by the pumping-pistons alternately, and means for opening communication between the trapping space between said eduction- 115 pipe and said working-barrel whereby on one movement of said pumping-pistons the fluid trapped in one of said spaces is permitted to pass into said eduction-pipe, and means whereby the fluid trapped in the 120 other of said spaces is admitted to said eduction-pipe by the opposite movement of said pumping-piston.

6. In a pump, the combination of a working-barrel, pumping pistons contained therein, an eduction-pipe communicating with said working-barrel, openings formed in said working-barrel leading to trapping spaces between said eduction-pipe and said working-barrel, a split flexible spring-actuated 125 130

valve in said working-barrel normally closing said openings in said working-barrel, said valves being opened by the suction action of the pumping-pistons whereby fluid is admitted alternately to said trapping spaces, and means for opening communication between one of said trapping spaces and the suction-pipe, while the other trapping space is closed upon one movement of the pump-

ing-pistons and reversing the same on the opposite movement of the pumping-pistons.

In testimony whereof, I the said HENRY B. WALKER, have hereunto set my hand.

HENRY B. WALKER.
